US00D688246S

(12) **United States Design Patent**
Lee

(10) **Patent No.:** US D688,246 S
(45) **Date of Patent:** ** Aug. 20, 2013

(54) **CONDUCTING TERMINAL**

(71) Applicant: **Aces Electronics Co., Ltd.**, Taoyuan County (TW)

(72) Inventor: **Kuang-En Lee**, Taoyuan County (TW)

(73) Assignee: **Aces Electronics Co., Ltd.**, Jhongli, Taoyuan County (TW)

(**) Term: **14 Years**

(21) Appl. No.: **29/441,412**

(22) Filed: **Jan. 4, 2013**

(30) **Foreign Application Priority Data**

Sep. 10, 2012 (TW) 101305311

(51) **LOC (9) Cl.** **14-02**

(52) **U.S. Cl.**

USPC **D14/433**

(58) **Field of Classification Search**

USPC D14/300-302, 308-313, 314, 348, D14/353-355, 432, 439-446; 361/679.02, 361/679.31, 679.5, 690, 694, 679.23, 801, 361/802; 312/332.1, 334.1; D19/81
